(57) **CLAIM**

The ornamental design for a belt buckle, as shown and described.

DESCRIPTION

FIG. 1 is a front elevational view of a first embodiment of my new design of a belt buckle

FIG. 2 is a rear elevational view thereof.

FIG. 3 is a right side elevational view thereof, the left side elevational view being a mirror image thereof.

FIG. 4 is a cross-sectional view taken along line 4-4 of FIG. 1 thereof.

FIG. 5 is a top plan view thereof.

FIG. 6 is a bottom plan view thereof.

FIG. 7 is a front elevational view of a second embodiment of my new design of a belt buckle.

FIG. 8 is a rear elevational view thereof.

FIG. 9 is a right side elevational view thereof, the left side elevational view being a mirror image thereof.

FIG. 10 is a cross-sectional view along line 10-10 of FIG. 7.

FIG. 11 is a top plan view thereof; and,

FIG. 12 is a bottom plan view thereof.
